(57) **CLAIM**

The ornamental design for a portable electric power tool body, as shown and described.

DESCRIPTION

FIG. 1 is a front, right and top perspective view of a portable electric power tool body showing our new design;

FIG. 2 is a rear, left and top perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a front, right and top perspective view of the portable electric power tool body in accordance with our new design illustrating a state in which environmental structures (a battery and a chainsaw blade) are attached to the portable electric power tool body.

The broken lines in the drawings illustrate the environmental structures or portions of the portable electric power tool body which form no part of the claimed design.

1 Claim, 9 Drawing Sheets
